UNITED STATES PATENT OFFICE

VICTOR GABRIEL GIRAUD, OF PARIS, FRANCE

CLOSURE

Application filed August 6, 1927, Serial No. 211,029, and in France April 19, 1927.

My invention relates to wooden closures and more particularly to that type of closure in which a plurality of ventilating openings are provided which permit one to see without being seen.

My invention is comprised in certain novel forms, construction, and combination of parts, the objects of which are to provide reliable devices for the purposes stated and to 10 cheapen the cost of manufacture, all of which will hereinafter be fully described and claimed.

In the drawings—

Fig. 1 is a perspective view showing the 15 outer side of the closure;

Fig. 2 is a section along the line 2—2 of Fig. 1;

Fig. 3 is a perspective looking from the rear of Fig. 1 and showing the inner side of 20 the closure;

Fig. 4 is a section along the line 4—4 of Fig. 3;

Fig. 5 is a section along the line 5—5 of Fig. 3;

Fig. 6 is a view similar to Fig. 1 of a modification;

Fig. 7 is a section along the line 7—7 of Fig. 6;

Fig. 8 is a view similar to Fig. 3 of this 30 modification;

Fig. 9 is a section along the line 9—9 of Fig. 8;

Fig. 10 is a section along the line 10—10 of Fig. 8;

Fig. 11 is a view similar to Fig. 1 of a third embodiment of the invention;

Fig. 12 is a section along the line 12—12 of Fig. 11;

Fig. 13 is a view similar to Fig. 3 of this 40 third embodiment;

Fig. 14 is a section along the line 14—14 of Fig. 13; and

Fig. 15 is a section along the line 15—15 of Fig. 13.

Referring to the drawings and more particularly to Figs. 1 to 5, a panel 1 is surrounded along its edges by a frame comprising two longitudinal strips 2 and two transverse strips 3. The said strips are fastened to the 50 edge of panel 1 by means of the usual mortise

and tension joint extending throughout the edge of the panel 1.

The panel 1 is provided with a plurality of transverse ventilating openings 5. The said 55 ventilating openings are shorter on the outer side of the closure than on the inner side as shown at 6 and 7. These openings are obliquely disposed in parallel relation. The sides of the opening being parallel and the ends tapered and obliquely disposed with 60 respect to the side, each opening has the form of prismoid whose bases are similar trapezoids and whose faces consist of two parallel trapezoids and two non-parallel but symmetrically disposed trapezoids.

Obviously such a structure possesses great 65 advantages over the well-known type of closure in which pivoted slats or obliquely disposed slabs of wood are used. To form the panel 1 it is merely necessary to cut the openings from a solid piece of wood thereby eliminating the assembly of any small parts.

The form of opening as will be recognized 70 by those skilled in the art cuts off all vision from the front side of the closure since in addition to the openings being obliquely disposed the ends of each opening not only extend away from each other toward the inner side of the closure but also are obliquely disposed. Such a form of opening increases the 75 visibility from the inner side of the closure.

Referring to Figs. 6 to 9 the panel 1 instead of being provided with a single row of openings is here provided with a double row as indicated at 5^a, 5^b. Each opening 5^a and 5^b is of 80 precisely the same form as previously described in connections with Figs. 1 to 5 as indicated at 6^a, 6^b and 7^a, 7^b. This type might be suitable where a larger closure member is 85 to be used.

Referring to Figs. 11 to 15, a panel 8 is provided consisting of a solid block of wood in which the openings 9 are cut. On the front or outer side of the panel 8 the opening is of 90 segmental form as shown at 10 and tapers from the rear of the panel. On the rear side of the panel the opening is given the form of a rectangle having curved ends as shown at 11.

Transverse holes 12 are provided adjacent 100

each end of panel 8 and are provided at each extremity with a washer 13. Disposed in said holes are suitable rods 14 the extremities of which 14' are riveted against the washers 13. One of the riveted ends is made slightly larger than the other and may receive a suitable hanging device if desired.

This form of closure is particularly suitable for heavy doors. The reenforcing rods 14 not only give the closure more strength and prevent warping but also provide a means for attaching a suitable anchorage which might become detached by the weight of the closure if fastened to the wood.

Having thus described my invention what I claim as new and desire to secure by Letters Patent is—

1. In a closure of the type described the combination of a solid wooden panel and a plurality of ventilating slots formed in said panel extending upwardly from the front side to the rear side of said panel the slot on the front side of the panel being of greater length than on the rear side of the panel for the purpose described, and the sides of said slots diverging from the front side to the rear side along lines lying in planes at acute angles to said panel.

2. In a closure of the type described the combination of a solid wooden panel and a plurality of ventilating slots formed in said panel extending upwardly from the front side to the rear side of said panel, two of the walls of said slot being parallel and two of the walls being tapered from the rear to the front of said panel and lying in planes at acute angles to said panel for the purpose described.

3. In a closure of the type described the combination of a solid wooden panel and a plurality of ventilating slots formed in said panel extending upwardly from the front side to the rear side of said panel, each of said slots having the form of a prismoid whose bases are similar trapezoids and whose faces consist of two parallel trapezoids and two non-parallel but symmetrically disposed trapezoids, said non-parallel trapezoids lying in planes at acute angles to said panel.

4. In a closure of the type described the combination of a solid wooden panel, a plurality of ventilating slots cut in said panel and extending upwardly from the front side to the rear side of said panel, said slots being of greater lengths on the front than on the rear side of said panel and the sides of said slots diverging from the front side to the rear side along lines lying in planes at acute angles to said panel, and metallic reenforcing means adjacent each end of said panel for the purpose described.

5. In a closure of the type described the combination of a solid wooden panel, a plurality of ventilating slots cut in said panel and extending upwardly from the front side to the rear side of said panel, said slots being

of greater lengths on the front than on the rear side of said panel and the sides of said slots diverging from the front side to the rear side along lines lying in planes at acute angles to said panel, a transverse hole adjacent each end of said panel, and metallic reenforcing rods disposed in said holes, the ends of said rods being flared for the purpose described.

6. In a closure of the type described the combination of a solid wooden panel, a plurality of ventilating slots cut in said panel and extending upwardly from the front side to the rear side of said panel, said slots being of greater lengths on the front than on the rear side of said panel and the sides of said slots diverging from the front side to the rear side along lines lying in planes at acute angles to said panel, a transverse hole adjacent each end of said panel, metallic washers disposed in each end of said holes and a metallic rod disposed in each of said holes, the ends of each of said rods being riveted against their respective washers for the purpose described.
